UNITED STATES PATENT OFFICE

2,526,157

APPARATUS FOR HEAT EXCHANGE
BETWEEN LIQUIDS

Torsten Ramén, Stockholm, Sweden

Application June 14, 1945, Serial No. 599,461
In Sweden August 7, 1941Section 1, Public Law 690, August 8, 1946
Patent expires August 7, 1961

1 Claim. (Cl. 257—245)

1

The present invention relates to apparatus for heat exchange between liquids of the kind in which a great number of conduits are arranged in a casing for the passage of one liquid, while the other liquid is conducted between or around said channels.

The object of the invention is to provide an improved heat exchange apparatus of said kind in which the conduit for the passage of one of the liquids may be inspected and cleansed from deposits and which at the same time has a good heat exchange capacity and is of compact construction.

The heat exchange apparatus according to the invention is characterized in that the heat exchanging part of the apparatus consists of a set of flat hollow and substantially rectangular hollow elements disposed in parallel relationship and spaced apart from each other, through which elements one of the liquids is conducted and which are so attached to frames holding the ends of the elements together that the elements together with said frames may be removed as a unit from the casing for inspection or cleansing.

According to a suitable embodiment of the invention each of the elements comprises two plates welded together along the edges, which plates are provided with longitudinal groove-shaped stampings, which stiffen the elements and which may be arranged opposite to each other and of such depth that they touch each other thereby together forming distance pieces between the two plates of an element.

The plates that form the elements are further preferably provided with projecting pressed out portions forming distance pieces between adjacent elements.

An embodiment of a heat exchange apparatus according to the invention is shown on the accompanying drawings.

Figs. 1 and 2 show two longitudinal sections at right angles to each other through the apparatus, the section in Fig. 1 being taken between two adjacent elements.

Fig. 3 shows a section taken along the line III—III in Fig. 1.

Fig. 4 shows on an enlarged scale a fragmentary side view of one of the elements included in the apparatus.

Fig. 5 shows a section through a pair of the elements taken along the line V—V in Fig. 4.

Figure 6 is a sectional view on an enlarged scale taken on lines VI—VI of Figure 2 and illustrating the manner in which the plate elements are attached to the frame elements.

2

Figure 7 is a sectional view taken along line VII—VII of Figure 6.

The heat exchange apparatus consists of a substantially rectangular, elongated casing 1 in which are inserted a great number of hollow flat parallel elements 2 which form channels for the passage of one liquid, while the other liquid flows through the spaces 3 between said elements. Each of the elements consists of two plates welded together at 4 along the edges. The open ends of the elements are welded to tray-like frames 5 and 6 respectively shown in Figures 6 and 7. As indicated, the open ends of the flat element are bent outwards and are welded to the adjacent elements in such a way that the welded, bent out parts together form a separating wall in the spaces between the elements, whereafter the ends of the set of elements thus welded together are welded to the frames 6 as shown at 18 in Fig. 6.

The casing 1 is provided with inlet- and outlet-pipes 7 and 8 for the liquid that is flowing through the spaces 3 between the elements. To the frame 5 is welded a flange 9, which is fastened between a flange 10 of the casing and a connecting pipe 11 for the connection of the heat exchanger with a supply- or discharge-pipe for the other liquid flowing through the elements. The other frame 6 is welded to a tube 12 on the end of which is screwed a flange 13 for connection to a pipe line. On the upper part of the casing 1 is welded a tube 14 which surrounds the tube 12 and together with the displaceable packing gland 15 forms a stuffing box, which is adapted to tighten against the tube 12. All the elements 2 together with the frames 5 and 6 and the parts fastened to the same form a single unit which can be loosened and taken out for inspection and cleansing. For this purpose at first the flange 13 has to be unscrewed and the gland 15 loosened. The pipe 11 is next detached after which the whole set of elements can be taken out through the bottom of the casing. While the whole set of elements is rigidly connected to the casing 1 by means of the flange 9, the other end of the set of elements is displaceable relatively to the casing by means of the stuffing box 14, 15 for permitting the elements and the casing to freely expand and contract during changes of temperature.

In the plates forming the elements longitudinal groove-shaped stampings 16 are made for stiffening the elements.

These stampings can be arranged opposite to each other and be so deep that they touch each

other, thereby forming together distance pieces between the plates in an element as shown in Figure 5.

Further button-shaped projections 17 are formed by pressing out the plates. The projections are preferably arranged in rows about half-way between the groove-shaped stampings 16 and form distance pieces between adjacent elements.

Having now particularly described the nature of my invention and the manner of its operation, what I claim is:

Apparatus for heat exchange between liquids, comprising, in combination, a casing, a set of flat, substantially rectangular hollow elements within said casing for the passage therethrough of one liquid, said elements being disposed in parallel relationship and spaced apart from each other, the other liquid being passed between and around said elements, each of said elements comprising two plates secured together along their longitudinal edges, said plates being provided with longitudinal grooves extending along the whole length of the elements and arranged opposite each other and of such a depth that they touch each other, thereby together forming distance pieces between the two plates and at the same time serving to stiffen the element against pressure from outside, said plates being further provided with projecting, pressed out small knob-shaped distance pieces serving to stiffen the element against pressure from within, said knobs being arranged in longitudinal rows about half-way

5 between the longitudinal grooves leaving free spaces between adjacent knobs for the liquid flowing along the outside of the elements, frames attached to the ends of said elements and so arranged that the elements together with said frames can be removed from the casing as a single unit for inspection or cleansing, means rigidly connecting the whole set of heating elements with the casing at one end, a stuffing box, the other 10 end of the set of elements being held tightly against the casing by said stuffing-box and being displaceable relatively to the casing, so as to permit the elements and the casing to expand and contact freely relatively to each other upon 15 changes in temperature.
